UNITED STATES PATENT OFFICE.

JESSE R. OAKLEY, OF SWISSVALE, AND ORRANGE H. CIVITTS, OF PITTSBURGH,
PENNSYLVANIA.

FURNACE-CHARGING BOX.

1,282,924.

Specification of Letters Patent. Patented Oct. 29, 1918.

Application filed August 17, 1917. Serial No. 136,682.

To all whom it may concern:

Be it known that we, JESSE R. OAKLEY and ORRANGE H. CIVITTS, citizens of the United States, and residents, respectively, of 5 Swissvale and Pittsburgh, both in the county of Allegheny and State of Pennsylvania, have invented certain new and useful Improvements in Furnace-Charging Boxes, of which the following is a specification:

10. Our invention relates to charging boxes, of the class used in charging scrap metal and similar materials into open-hearth furnaces, and more particularly to the construction of integrally formed cast charging boxes 15 made of steel.

One object of our invention is to provide a charging box having improved means whereby the casting of integrally formed charging boxes is facilitated and the formation 20 of steel charging boxes in a metallic or chill mold is made possible without excessive cost due to loss caused by making cracked or otherwise defective castings.

A further object of our invention is to provide 25 a metallic integrally formed cast charging box of improved construction and having novel means wherein the strength and durability of the charging boxes are increased and whereby the weight of the 30 charging boxes may be materially reduced without undue loss in strength or reduction in the durability of the charging boxes.

Referring now to the drawings, forming 35 part of this specification, Figure 1 is a plan showing, in open position, a sectional chill mold adapted for use in making the improved cast metal charging box forming a novel feature of this invention.

Fig. 2 is an end elevation of the chill mold 40 shown in Fig. 1.

Fig. 3 is a longitudinal side elevation showing the mold with the parts in assembled position, and having a charging box formed therein, the mold and charging box 45 being illustrated in position at the completion of the casting operation.

Fig. 4 is a transverse section of the mold, shown in Fig. 3, the section being taken on the line IV--IV of Fig. 3.

50. Fig. 5 is a plan of the chill mold in assembled position.

Fig. 6 is a plan showing a preferred form of charging box embodying our invention.

Fig. 7 is a sectional side elevation of the

charging box shown in Fig. 6, the section 55 being taken on the line VII--VII of Fig. 6.

Fig. 8 is an end elevation showing one end of the charging box of Figs. 6 and 7.

Fig. 9 is an end elevation similar to that of Fig. 8, showing the other or opposite end 60 of the charging box of Figs. 6, 7, and 8.

In the accompanying drawings, the letter A designates one and B the other of the two sections or members of the improved chill mold. As shown, the members A and B are 65 pivotally connected at one side by hinge pins 2 which fit into registering holes in the pairs of lugs or ears 3, 3 on the member A and adjacent lugs 4, 4 on the other member B. The member A has a bottom 5, sides 6, 6 70 and a closed end 7, the end 7 conveniently forming a flat base or support on which the mold stands upright during the metal pouring or casting operation. The opposite end of the member A is open, not having a closure 75 corresponding to the base or end 7. (See Figs. 1, 2, and 3). A series of transverse stiffening ribs 8 on the exterior of the member A serve to strengthen this member and prevent warping thereof. 80

The other member B of the mold, which is hollow or recessed, has a bottom formed by the parts 9, 9^a and 9^b, sides 10, 10, and transverse partitions 11, 11 forming ends, the ends 11, 11, however, not being located 85 at the extreme ends of the member B, and serving to connect the parts 9^a and 9^b to the part 9 of the bottom. The bottom 9, sides 10, 10, and partitions 11, 11, of the member B project into the member A (see Fig. 4), 90 and the member B is provided with flanges 12, 13 which overlap corresponding flanges 14, 15 on the sides 6, 6 of the member A. The transverse partitions 11, 11 on the member B form bottoms or ends for the core receiving pockets 16 and 17 of the sectional chill mold formed by the members A and B when assembled in pouring position, and also forming ends for the recess 18 in the hollow member B. A transverse rib 19 in 100 the recess connects the sides 10, 10 of the member B. (See Figs. 3, 4, and 5).

The inner surface 20 of the sides 6, 6 of the mold section A is formed of a series of reverse curves to provide a corrugated surface with the parallel corrugations extending transversely across the width of each side 6, and the inner surface 21 of the bottom

5 of the member A is curved transversely. (See Figs. 2 and 4).

The adjacent surfaces 22 of the sides 10, 10 of the member B are similarly corrugated 5 and the valleys in the corrugations in the surfaces 22 of the member B are staggered with respect to the valleys in the surfaces 20 of the sides 6, 6 of the member A. In this way the adjacent corrugated chill surfaces 10 20, 22 are made parallel and provide cavities which will form a charging box C having transversely corrugated sides of substantially uniform thickness throughout the length thereof.

15 The surface 23 of the bottom 9 of the mold member B is transversely curved so as to coact with the curved surface 21 of the bottom 5 of the member A in forming an inwardly dished or curved bottom on the 20 charging boxes.

A series of protuberances 23^a will be provided on the inner surface of the bottom 9 of the mold section B so as to form a series of cored holes 30^a in the bottom 30 of the 25 cast charging boxes, these holes providing for drainage of water from the charging boxes when exposed to the elements as they are during use in the stock yard of the open-hearth furnace plant.

30 The recesses or pockets 16 and 17 formed in the ends of the sectional mold have dry sand cores 24 and 25 fitted therein to form the flanges and lugs on the ends of the charging boxes C.

35 When desired green sand may be molded in the pockets 16 and 17 instead of using dry sand cores, and in such case patterns will be employed to shape the cavities in the green sand, in providing for the flanges and 40 lugs on the charging boxes.

In making charging boxes embodying our invention, a sectional metallic mold like that shown is assembled in the open position shown in Figs. 1 and 2, the mold section A 45 resting on its end flanges 8, 8. When dry sand cores are used, the cores are then assembled in the pockets 16 and 17, in the ends of the mold section A, and are secured therein so as to permit of handling the mold.

50 The top section B of the mold is then closed on the bottom section and the sections A and B are then fastened together, preferably by means of U-clamps 26 and wedges 27 in the manner shown in Fig. 4. The mold is then 55 lifted into the upright position shown in Fig. 3, the assembled mold resting on its base 7. A gate 28 is then provided on the upper end of the mold, as shown Fig. 3, and the mold is in readiness for the casting operation.

The molten metal is then poured through the gate 28 into the mold so as to entirely fill the cavities in the mold, the pouring operation being effected as rapidly as possible.

60 The metal forming the casting or charging

box is rapidly cooled as it comes in contact with the chill surfaces of the mold, so that the mold may be opened and the charging box may be removed from the mold immediately after the completion of the casting 70 operation, and in this way the danger of cracking of the mold by shrinkage thereof during cooling in the mold is avoided and overcome. As soon as the charging box is cooled sufficiently the mold is laid lengthwise 75 on the ground or floor and after the wedges 27 are loosened and the U-clamps 26 are removed, the mold is opened and the cast charging box is removed.

After the charging box becomes cooled 80 the sprue is removed from its end and after being annealed, the charging box preferably being annealed, it is in readiness for use.

The above described operations are then carried out in the use of the mold in making 85 successive charging boxes.

By reference to Figs. 6 to 9, which show the construction of our improved charging box C in detail, it will be seen that the charging boxes have corrugated sides 29 90 which are of substantially uniform thickness throughout the length of the boxes, and that the transversely curved bottom 30 of the box is curved inwardly. As the sides of the charging box are formed between the 95 chill surfaces 20, 22 of the mold, the shrinkage in the length of the mold, which is unavoidable, is uniformly distributed over the entire length of the mold by reason of the corrugated side surfaces 20, 22, in which 100 the sides of the charging boxes are formed, which grip the metal of the charging boxes during solidification thereof at each of the reverse curves forming the corrugations. The sand cores in which the ends of the 105 charging boxes are formed being compressible, the compression or crushing of the said cores also assists in preventing cracking of the cast boxes at the junction of their ends 31, 32 and sides 29, 29 when cooling or 110 solidifying, while the hinged mold members A and B permit of the mold being quickly opened as soon as the charging box is cooled sufficiently to become solid after completion of the pouring operation.

115 The ends 31 and 32 of the charging boxes have the flanges 33 and lugs 34 usually provided thereon for use in handling the charging boxes to transport the filled boxes and in charging the transported material into 120 the open-hearth furnaces.

The advantages of our invention will be appreciated by those skilled in the art. By the provision of a charging box having transversely corrugated sides of substantially uniform cross section, and an inwardly curved bottom, a charging box of great strength and relatively light weight is obtained.

125 By employing a chill mold and providing

the sides and bottom of the mold with curved surfaces instead of flat or plane surfaces, in forming the charging boxes, the casting of an integrally formed charging box having a bottom, sides, and closed ends and embodying our invention is made possible.

Modifications in the construction of the apparatus used in casting charging boxes 10 may be made, and the shape of the charging box also may be changed without departing from the invention as defined in the appended claims.

We claim:

15. 1. Apparatus for casting integrally formed charging boxes comprising a sectional metallic mold having chill surfaces adapted to form the sides and bottom of the charging boxes, the chill surfaces of the mold being 20 corrugated, and pockets in the ends of said mold in which the ends of the charging boxes are cast, said pockets being constructed and arranged to receive sand molds, in which the ends of the charging boxes are 25 formed, and means for securing the mold sections in assembled relation during the casting operation.

2. Apparatus for casting integrally formed charging boxes comprising a sectional metallic mold having chill surfaces adapted to form the sides and bottom of the charging boxes, the chill surfaces of the mold which 30 form the sides of the charging boxes being

corrugated and those forming the bottom of the charging boxes being transversely curved, pockets in the ends of the sectional mold, said pockets being constructed and arranged to receive sand molds in which the ends of the charging boxes are formed, and means for securing the mold 40 sections in assembled relation during the casting operations.

3. A cast metal charging box having integrally formed end, side, and bottom portions, the inner surface of the bottom portion being convex and the outer surface concave, and the inner and outer surfaces of the side portions being corrugated and of substantially uniform thickness.

4. A cast metal charging box having end portions integrally formed with corrugated side portions and a transversely curved bottom portion, the side portions of said charging box being of substantially uniform thickness throughout the length thereof.

5. A cast metal charging box, integrally formed and having end portions, corrugated side portions, and a transversely curved bottom portion.

6. A cast metal charging box, integrally formed and having a bottom portion, end portions and corrugated side portions.

In testimony whereof we have hereunto set our hands.

JESSE R. OAKLEY.
ORRANGE H. CIVITTS.
